AIMING DEVICE FOR MORTARS

Joseph Raymond Jasse, Paris, France, assignor to Hotchkiss-Brandt, Paris, France, a body corporate of France

Filed July 16, 1958, Ser. No. 749,011

Claims priority, application France July 18, 1957

7 Claims. (Cl. 89—41)

The present invention relates to aiming devices for mortars and like firearms intended to be as a rule fired in any direction in azimuth.

The aiming device of a mortar generally comprises a sighting apparatus fixed on a mount connected to the mortar barrel by releasing means, a reference or aiming mark disposed at a certain distance from the mortar and suitable control means for the mount whereby the mortar is aimed.

In general, the mortar is put in an initial direction termed an observation or datum direction determined, for example, by means of two suitably spaced aiming-posts. In order to aim the mortar, the deflection drum of the sighting apparatus is turned so that the plane containing the axis of the aiming telescopic sight and the axis of rotation of the deflection drum is parallel with the axis of the mortar barrel, the horizontality control device of the mortar is actuated to bring the bubble of the transverse spirit level between reference marks and the biped mount is moved by pivoting the mortar barrel in the socket or seat of the base-plate on which the rear end of the barrel rests, until the center of the cross wires of the sight of the sighting apparatus is in alignment with the aiming-posts determining the observation direction.

If, in firing, the mortar is displaced out of the line of fire due to the displacement of the base due to the effect of the reaction of firing the shot, it is always possible to recover the desired position of the barrel by acting on the elevation and horizontally controls so as to bring the bubbles of the spirit levels between the reference marks and thereafter acting on the traversing control so as to bring the center of the cross wires of the sight on one of the aforementioned aiming posts, without touching the sighting apparatus.

If it is required to effect a fire switch through a given angle, that is, to change the direction of fire, for example through a certain angle toward the right, the known procedure is adopted in pivoting the deflection drum through the same angle toward the left and thereafter pivoting the mortar barrel toward the right until the center of the cross-wires of the sight is once more on the aiming-post.

But if this post is not at infinity, that is, if the new line of sight is not parallel with the previous line of sight, the angle through which the barrel turns is less than the desired angle. The difference is greater as the aiming-post is nearer the mortar, since it is only when this post is at infinity that the new line of sight is parallel with the previous line of sight and that the desired fire switch is obtained.

Now, in practice, it is sometimes necessary to fire from a defiladed position (cave, shell hole, etc.) which does not permit an aiming mark to be placed at a sufficient distance (about 50 meters) to suitably reduce the aiming error in azimuth because the aiming mark is not at infinity (parallax error).

If the aiming mark can only be positioned at a lesser distance from the mortar, for example, at 1.5 meters from the socket of the base plate, it is practically impossible to fire with sufficient accuracy in using a conventional aiming

2

device notably in the case of firing in any direction in azimuth.

The present invention avoids these disadvantages.

The object of the invention is to provide an improved 5 aiming device for mortars and like fire arms which are adapted to be fired in all directions in azimuth, at least in directions which make with one another very large angles, this device permitting putting the mortar in observation by means of a reference device which is located 10 very near the mortar (for example less than 2 meters), which permits firing even when this mortar is in a very defiladed position.

Said device comprises in combination with a sighting 15 apparatus provided with a telescopic sight: support means fixed to the mount of the mortar and forming a slideway along which said sighting apparatus is movable as desired, said slideway being oriented in such manner as to permit reducing the distance in plan from the axis of the telescopic sight of said apparatus to the vertical pivot axis of 20 the mortar in the course of fire switches in azimuth while regulating said distance between two given limits, and a reference device so adapted that by observing the latter through the telescopic sight of the sighting apparatus it is possible to determine instantaneously and without ambiguity that the axis of the telescopic sight is perpendicular 25 to said reference device.

Said reference device could be constituted notably by 30 a mirror having two flat faces disposed at 90° to one another, or a prism equivalent to this mirror; or a series of projections comprising flat edges located in the same plane and lateral faces perpendicular to said plane whereby the line of sight of the telescopic sight is perpendicular to said plane only when said lateral faces are not visible in the telescopic sight.

35 Obviously, the reference device should have sufficient length so that when the fire arm changes direction, the prolongation of the axis of the sight perpendicular to this device still encounters this device. Now, if the sighting apparatus were fixed directly to the mount in the usual 40 manner, that is, at a point relatively distant from the vertical axis about which the fire arm barrel turns in the course of fire switches in azimuth—which axis in the case of a mortar intersects the point at which the rear of the barrel is supported on the base-plate anchored in the ground—this reference device would have to have a rather great length and in any case a length greater than the diameter of the circle described by the telescopic sight when firing in all directions in azimuth.

Owing to the fact that the sighting apparatus is carried 50 by the aforementioned slide-way fixed on the mount, it is possible to shift the sighting apparatus considerably toward the vertical axis about which the barrel turns and in this way the lateral displacement of the line of sight of the telescopic sight is reduced, which correspondingly reduces the required length of the reference device. Thus, owing to the aforementioned combination, the reference device has its transverse dimensions limited to some tens of centimeters.

Briefly, the aiming device of the invention permits 60 eliminating any parallax, since the successive lines of sight remain parallel with one another because they are all perpendicular to the reference device and this is obtained with a reference device which takes up a minimum amount of space owing to the aforementioned slide-way support carrying the sighting apparatus.

65 Further features and advantages of the invention will be apparent from the ensuing description, with reference to the accompanying drawings, to which the invention is in no way restricted.

In the drawings:

70 Fig. 1 is an elevational view of a mortar provided with an aiming device embodying the invention;

Fig. 2 is a corresponding plan view;

Fig. 3 is an elevational view on an enlarged scale of means constituting the slideway support for the sighting apparatus;

Fig. 4 is a corresponding plan view thereof, partly in section, taken along line 4—4 of Fig. 3;

Fig. 5 is a vertical cross-sectional view taken along line 5—5 of Fig. 3;

Fig. 6 is a diagrammatic view of the forward end of the optical or telescopic sight of the sighting apparatus;

Figs. 7 and 8 are diagrammatic front views of the reference device showing what is seen of this device through the telescopic sight in day time and at night respectively;

Fig. 9 is a diagrammatical vertical elevational view of the mirror having two perpendicular faces forming part of the reference device showing the directions of the incident and reflected rays;

Fig. 10 is a diagrammatic plan view of two positions of the sight combined with a reference device comprising a series of plates which must be viewed solely by their forward edges of it is desired that the reference axis be, and remain, perpendicular to this reference device;

Figs. 11 and 12 show the appearance of this reference device through the telescopic sight when the reference axis is respectively perpendicular and oblique to the reference device, and

Fig. 13 is a diagram showing use of a flat mirror.

In the embodiment shown in Figs. 1 and 2, the invention is applied to a mortar of conventional type comprising a mortar barrel A which rests at its rear end, through the medium of a ball in a spherical socket or seat a of a baseplate B adapted to be anchored in the ground as soon as the first rounds have been fired and, at its forward end, on a rotatable mount C having three parts: a biped b, a clamping device c for clamping the barrel A in position and a release device d interconnecting the biped b and the device c and adapted to withstand, at least up to a certain force, the recoils of the barrel; the biped is connected to the release device by a yoke e and a traversing screw f.

The aiming device of the invention is combined with this mortar and comprises in combination: support means generally indicated by the reference character D—this support means providing a slideway—a sighting apparatus E adjustable along said slideway and a reference device F.

The support means D is shown on a small scale in Figs. 1 and 2 and on an enlarged scale in Figs. 3—5.

In this embodiment, the support means is adapted to be fixed to the biped b of the mount C and comprises four parts situated between the biped and the apparatus E: a first support member 1 adapted to be fixed to the mount; a straight arm 2 forming a slideway; an elastically yieldable connecting device 3 connecting the arm 2 to the support member 1; and a slide 4 movable along the arm 2 and adapted to receive the sighting apparatus E.

The support 1 comprises a base 5 to which is connected a tube 6 carrying at its end two members 7 and 8 which surround the tube 6. A male dovetail 11 (Fig. 4) is fixed to the ends of the members by a screw 9 and a dowel 10 and is adapted to be engaged in a female dovetail 11^a (Fig. 2) formed in the yoke e of the biped.

The arm 2 constitutes a rectilinear slideway and has a prismatic cross-sectional shape, for example hexagonal, and is preferably tubular (Fig. 5). This arm is connected to the base 5 of the support 1 by the elastically yieldable device 3 which permits maintaining this arm in a given orientation while allowing it to deviate from this orientation elastically under the effect of lateral forces and in particular forces of inertia which act on this arm, on the slide 4 and on the sighting apparatus E carried by the slide, when firing each round.

This elastically yieldable device is constructed in the

following manner in the embodiment shown in Fig. 4. Connected to the base 5 by a flange 12 and screws 13 is a housing 14 on which is thread an annular cover 15. Bearing against the transverse wall of the housing 14 through the medium of three balls 16 is the base 17 of a member 18 in which is formed a conical recess or seat 19. Fitted into this seat and held therein by a screw 20 is a conical male end 21 of the arm 2. The base 17 of the member 18 is held elastically against the balls 16 by springs 22 which are concentric with the member 18 and bear against the base 17 and against a washer 23, which latter rests against the inner annular face of the cover 15.

The base 17 is prevented from rotating relative to the housing 14 due to the fact that the balls 16 are disposed in conical recesses 16^a and 16^b provided in the members 17 and 14.

As mentioned hereinbefore, owing to the springs 22 the axis U—U of the arm 2 is maintained in a fixed direction from which it can be displaced elastically. This direction is chosen (see Figs. 1 and 2) in such manner that it is oblique relative to the longitudinal axis V—V of the barrel A in both the vertical and horizontal planes, the two axes U—U and V—V forming between each other an angle u in the vertical plane (Fig. 1) and an angle v in the horizontal plane (Fig. 2).

Preferably, the angle u is so chosen that the arm 2 is horizontal for a mean firing angle of

$$\frac{45+80}{2} = 63^\circ$$

this value of the angle u affording the most convenient position found in experience for the sighting apparatus E placed at the free end of the arm 2 (Figs. 1 and 2) irrespective of the angle of elevation.

The angle v in the horizontal plane is preferably about 10 to 20°, which permits avoiding, as will be explained hereinafter, dead angles in respect of the sighting apparatus E when firing in any direction in azimuth.

The slide 4, which is movable along the arm 2, forms a clamp on this arm. It consists of a main portion 24 which has at its upper part 25 a female dovetail for receiving the sighting apparatus E, this portion also forming by two lugs 26 one of the jaws of the clamp and by a depending portion 27 a support lever. Pivoted to the latter by means of the pin 28 is a second lever 29 constituting a second jaw 30 provided with clamping teeth 31. A spring 32 disposed between the two levers 27 and 29 tends to swing the jaw 30 in a direction which applies the teeth 31 against the arm 2 with sufficient force for maintaining the clamping slide 4 and the sighting apparatus E in position. To move the unit (4—E) along the arm 2 it is therefore sufficient to take hold of the two levers 27 and 29 in one hand and to compress the spring 32 so as to separate the two jaws 30 and 26.

The sighting apparatus E is of any conventional type permitting aiming in azimuth and elevation owing to the provision of the screw 33 (elevation), the possibility of turning the deflection drum and the provision of the fine deflection adjustment screw 34 (Fig. 1), which permits shifting in elevation and azimuth the line of sight W—W (Figs. 1 and 2) of a telescopic or optical sight 35 forming part of the sighting apparatus. This telescopic sight is capable of being looked into from above in the known manner, the eye-piece 36 being turned upwardly and its axis being disposed at 90° to the line of sight W—W, thus providing the gun-layer with a comfortable position at the side of the fire arm when aiming.

The sight 35 is completed, according to the invention, by means permitting an easy positioning of its optical axis W—W both during the day time and at night.

This sight, which comprises the conventional cross wires 37 (Fig. 6), further comprises at its forward end a flap 38 (Figs. 1, 2 and 6) which is pivoted at 39 and is raised when aiming as shown in Figs. 1 and 6. This flap

comprises in its middle a wide black line 40 which stands out against a white background 41.

Further, provided within the tube of the sight 35 toward its forward end is a translucent screen 42 (Fig. 6) which is substantially in the form of a horse-shoe or a U and which, illuminated by an electric lamp 43 placed behind it, constitutes at night an easily located light source. This electric lamp 43 is fed with current by a battery which could be disposed either in the sight or in the clamp support 4.

The unit described hereinbefore is completed by the reference device F. This device comprises a tripod 44 (Figs. 1 and 2) provided with a spherical spirit level 45 permitting insuring that a support 46 is in a horizontal position. The support 46 carries a reflector system comprising two flat mirrors 47 and 48 disposed at 90° to one another so that any incident ray, such as the ray R₁ or R₂ (Fig. 9), is reflected in a direction parallel with itself, that is, in directions R'₁ or R'₂ as known per se.

It will be observed that the support 46 for the mirrors is mounted relative to the tripod 44 for rotation about the axis X—X which is vertical when the bubble 45 of the level is between its reference marks. The support 46 carries on its upper end a small arm 49 which can be moved to a position parallel with the mirrors but which in its extended position is normal to the joint line 50 of the two mirrors 47 and 48 (Figs. 7, 8 and 9).

The unit described hereinbefore operates in the following manner:

The mortar having been placed in its observation direction S—S (Fig. 2), the reference device F is preferably placed in a position which is offset relative to the observation plane S—S at an angle s, and the mirror is oriented in such manner that the arm 49 is in line with the centre of the seat a and substantially with the axis of the sight 35 of the sighting apparatus. The image of the end of the sight therefore appears in substantially the middle of the mirror which is the best position for firing in any direction in azimuth. The deflection corresponding to the angle s will be noted; it is the observation angle.

Before firing, it is necessary, as is known, to determine the safe elevations, that is, the minimum elevation corresponding to the highest obstacle over which the line of fire must pass and maximum elevation corresponding to the lowest obstacle under which the line of fire must pass.

To determine the safe elevations, the deflection drum of the sighting apparatus is adjusted in such manner as to render the plane of sight parallel with the plane of fire and the sighting apparatus is moved along the arm 2 to its extreme forward position where it is located, relative to the barrel, substantially in the position it would occupy if it had been mounted directly on the yoke e of the biped b except for a slight difference in the lateral distance relative to the median axis of this yoke, this distance being slightly increased (requirement of construction).

With the sighting apparatus in this position, the minimum and maximum elevations are determined for each possible direction of fire in the usual manner. The telescopic sight 35 is pivoted about its horizontal axis so that its optical axis W—W becomes parallel with the axis V—V of the barrel. This position could, furthermore, be distinctly indicated, according to the invention, by an interlocking device, for example, having a ball and spring arrangement, provided between the sight and its support carried by the sighting apparatus. Then, by means of the elevation wheel of the mortar, the barrel and the sighting apparatus are moved simultaneously so that the line of sight of the sight is flush with the top of the obstacle.

By acting on the elevation knob of the sighting apparatus, the elevation bubble is brought between the reference marks and the minimum (or maximum) elevation is read off the graduation of the elevation sector.

After having returned the sighting apparatus to its

initial position, in which it is pointed at the mirror, the unit is ready for firing in any direction in azimuth.

It will be understood that during firing, the mirror is left untouched; this mirror in fact replaces a reference point at infinity.

Let it be assumed that it is required to fire in the direction T—T (Fig. 2) for which direction the axis V—V must be brought from the observation direction S—S, which corresponds to a fire switch to the right through an angle t (Fig. 2).

As the observation angle is equal to s to the left, the gun-layer effects the deflection (s+t) to the left and then orders a displacement of the barrel to the right, while he aims in the following conditions:

15 In the day time, he pivots the whole of the mortar about the vertical axis Y—Y intersecting the center of the seat a and thus brings the center of the image 37^a of cross wires 37 of the sight into coincidence with the middle of the black line 40^a of the image 38^a of the background 41 appearing in the double mirror 47—48, as shown in Fig. 7.

At night, the gun-layer causes the center of the cross wires to be projected at 37^a (Fig. 8) on the axis of the image 42^a of the suitably illuminated translucent screen 42.

25 It will be easily understood that the coincidences 37^a, 40^a (Fig. 7) or 37^a, 42^a (Fig. 8) are only possible so long as the reflected ray has the same direction in plan as the incident ray, which necessarily implies that this ray is perpendicular to the mirror.

30 Consequently, when coincidence is obtained, it is certain that the line of sight W—W of the sight is—irrespective of the position of the mortar and sight—perpendicular to the line of intersection 50 of the two mirrors and, therefore, makes an angle s with the observation direction S—S. The line of sight can only be more or less offset laterally therefrom depending on the amplitude of the fire switch, and this offset in lateral translation is, as is known, quite negligible bearing in mind the dimensions of the target and the dispersion of the fire.

40 Thus the axis V—V of the barrel is definitely directed in direction T—T corresponding to the direction of fire to be effected after the setting of the fire switch angle t and the following reference setting.

The fire switch thus obtained without the slightest error of parallax is a consequence of the utilization of the double mirror 47—48 which provides, owing to the coincidences of the images 40 or 42^a (Figs. 7 and 8) and of the cross wires 37^a, the certainty that the lines of sight remain constantly parallel with the initial line of sight and in other words affords the equivalent of a reference mark at infinity.

45 This result would be obtained even if the sighting apparatus E were fixed directly in the dovetail 11^a of the yoke e of the mount C (Fig. 2) but, in this case, owing to the coincidences of the images 40 or 42^a (Figs. 7 and 8) and of the cross wires 37^a, the certainty that the lines of sight remain constantly parallel with the initial line of sight and in other words affords the equivalent of a reference mark at infinity.

50 This result would be obtained even if the sighting apparatus E were fixed directly in the dovetail 11^a of the yoke e of the mount C (Fig. 2) but, in this case, owing to the coincidences of the images 40 or 42^a (Figs. 7 and 8) and of the cross wires 37^a, the certainty that the lines of sight remain constantly parallel with the initial line of sight and in other words affords the equivalent of a reference mark at infinity.

55 As mentioned hereinbefore, this would lead to a prohibitive size of the reference device F.

60 This is avoided owing to the support D forming part of the combination of the invention. It can be seen that as the sighting apparatus E is moved away from the elastically yieldable device 3 toward the free end of the arm 2, the circle described by the pivot axis of the telescopic sight in the course of fire switches decreases progressively. Thus in the position of the sighting apparatus shown in Figs. 1 and 2, the circle becomes that shown by the line II which has a very small radius; the

70 extreme lines of sight are then E³—W³ and E⁴—W⁴.

which can fall within the set of mirrors shown in the drawings, the length of which can therefore be restricted to some tens of centimeters.

The double obliquity u, y given to the axis $U-U$ of the arm 2 provides the additional advantage of eliminating any dead angle in the aiming, that is to say for all directions of fire there is at least one position of the sighting apparatus E along this arm for which the line of sight is not intersected by the barrel, which occurs for a range of directions of fire when the telescopic sight occupies a fixed position on the mount.

Thus, in Fig. 2, assuming that the reference device is at H^1 and the sight is disposed at 35^a , it is clear that the line of sight 35^a-W^5 would intersect the barrel A, whereas the line of sight $W-W^6$ passes over this barrel when the sighting apparatus E is in the illustrated position toward the free end of the arm.

The reference device F described hereinbefore has the advantage of permitting obtaining a correct aim irrespective of the elevation of fire or more precisely the inclination relative to the vertical of the optical axis of the sight 35 at the moment of aiming, since whatever the direction of the incident ray R_1 or R_2 the reflected ray R'_1 or R'_2 remains parallel with the incident ray and is received in the sight (Fig. 9).

Fig. 10 shows a modification of the reference device F^1 which gives the same result.

According to this modification, the two mirrors at 90° of the first embodiment are replaced by a reference device or flat slide F^1 formed by a sort of grid or series of parallel projections or plates 50 whose forward edges 51, adapted to be turned toward the sight 35 , as situated in the same plane ZZ which is parallel to slide F^1 . When the aim is correct, this plane must be perpendicular to the line of sight $W-W$ the sides 52 of these plates 50 which are perpendicular to slide F^1 being then parallel with the line of sight. Thus, if the suitable aim is obtained, that is, if the line $W-W$ is perpendicular to the plane ZZ, the series of blades is viewed simply from the edges 51 as shown in Fig. 11. If, on the other hand, the sight is disposed at 35^a (Fig. 10) so that the line of sight is oblique to the plane ZZ and is incorrect, the gun-layer observes in the eye-piece of the sight 35^a the blades 50 both from the edges 51 and their large sides 52 which indicates that the mortar must be turned a further distance about the axis $Y-Y$ to obtain that the view in the sight of the reference device F^1 be in conformity with that shown in Fig. 11.

Fig. 13 shows a modification of the reference device which comprises a single flat mirror 53 whose length corresponds to that of the two mirrors of the first example. However, in this modification which is perfectly suitable when the sight is disposed horizontally at 35 at the level of the median horizontal line of the mirror, it is essential to incline this mirror to the position shown at 53^a if the sight is disposed lower down at 35^b and has an ascending line of sight.

Although specific embodiments of the invention have been described, many modifications and changes may be made therein without departing from the scope of the invention as defined in the appended claims.

Having now described my invention what I claim as new and desire to secure by Letters Patent is:

1. A firearm including at least one rotatable portion mounted rotatably about a vertical axis and a barrel connected with said rotatable portion and the longitudinal axis of which may be inclined relatively to said vertical axis; an aiming apparatus comprising in combination: a reference device spaced from said vertical axis and of a relatively small length compared with the distance thereof from said vertical axis to determine whether a line of sight passing close to said vertical axis is perpendicular to said reference device, and an aiming device comprising a support element which is rigidly and laterally connected with said rotatable portion, a rectilinear slideway fixed on

said support element so as to be oblique with respect to the longitudinal axis of the gun barrel both in vertical direction and in horizontal direction, a slide movable along said slideway, and a sighting device with a line of sight carried by said slide, so that the displacement of the latter along said slideway makes it possible to reduce the distance in plan from said line of sight to said vertical axis of rotation of the rotatable portion of the firearm to a value which is, at most, equal to the length of the reference device.

2. In combination: a firearm including at least one rotatable portion mounted rotatably about a vertical axis and a gun barrel the longitudinal axis of which may be inclined relatively to said vertical axis, and an aiming apparatus for said firearm comprising: a reference device spaced from said vertical axis and of a relatively small size compared to the distance thereof from said vertical axis to permit determining whether a line of sight passing close to said vertical axis is perpendicular to said reference device, and an aiming device comprising a support element rigidly and laterally connected with the rotatable portion of the firearm, a rectilinear slideway fixed on said support element so as to be oblique relatively to the longitudinal axis of the gun barrel both in vertical direction and in horizontal direction, a slide movable along said slideway, and a sighting device with a line of sight carried by said slide in such a manner that the displacement of the latter along said slideway makes it possible to reduce the distance in plan from said line of sight to said vertical axis of rotation of the rotatable portion of the firearm to a value which is, at most, equal to the length of the reference device.

3. The combination according to claim 2, wherein said firearm is a mortar which comprises: base plate, said gun barrel being mounted pivotably on said plate about a fixed pivoting center and a mount of adjustable height on which rests and is fixed on the gun barrel which forms with said mount said portion of the firearm which is rotatable about said vertical axis, said support element of the slideway being fixed laterally on said mount.

4. A firearm including at least one rotatable portion mounted rotatably about a vertical axis and a gun barrel connected with said portion and the longitudinal axis of which may be inclined relatively to said vertical axis; an aiming apparatus comprising a support element rigidly and laterally fixed on said rotatable portion of the firearm, a rectilinear slideway fixed on said support element so as to be oblique relatively to the longitudinal axis of the gun barrel both in vertical direction and in horizontal direction, a slide movable along said slideway, and a sighting device with a line of sight carried by said slide in such a manner that the displacement of the latter along said slideway makes it possible to minimize the distance in plan from said line of sight to said vertical axis of rotation of the rotatable portion of the firearm.

5. A firearm including at least one rotatable portion mounted rotatably about a vertical axis and a gun barrel connected with said portion and the longitudinal axis of which may be inclined relatively to said vertical axis; an aiming apparatus comprising a support element rigidly and laterally fixed on said rotatable portion of the firearm, a rectilinear slideway, elastic means for fixing said slideway on said support element, so that said slideway, when in a position of rest established by the elastic means, is oblique with respect to the longitudinal axis of the gun barrel both in vertical direction and in horizontal direction, a slide movable along said slideway, and a sighting device with a line of sight carried by said slide in such a manner that the displacement of the latter along said slideway makes it possible to reduce the distance in plan from said line of sight to the vertical axis of rotation of the rotatable portion of the firearm.

6. An aiming device according to claim 5, wherein said support element includes a cup comprising a bottom and a flange spaced from said bottom, said flange being de-

tachable, said arm comprising a base parallel to said bottom, balls interposed between said bottom and said base, and an elastic device interposed between said base and said flange to urge the base against said bottom through the medium of said balls.

7. A firearm including at least one rotatable portion mounted rotatably about a vertical axis and a gun barrel connected with said portion and the longitudinal axis of which may be inclined relatively to said vertical axis; an aiming apparatus comprising in combination: on the one hand, a reference device spaced from said vertical axis and which comprises a flat slide of a relatively small length compared to the distance between the vertical axis and said reference device and adapted to be horizontal in operative position, and a series of projections on said slide, said projections having extremities in a plane parallel to said slide and lateral faces perpendicular to said slide, and, on the other hand, an aiming device comprising a support element rigidly and laterally fixed on the rotatable portion of the firearm, a rectilinear slideway

5

10

15

20

fixed on said support element so as to be oblique relatively to the longitudinal axis of the gun barrel both in vertical direction and in horizontal direction, a slide movable along said slideway, and a sighting device with a line of sight carried by said slide in such a manner that the displacement of the latter along said slideway makes it possible to reduce the distance in plan from said line of sight to the vertical axis of rotation of the rotatable portion of the firearm to a value which is, at most, equal to said length of the reference device, a correct aiming being realized when said line of sight is parallel to said lateral faces of the projections of the rule.
